UNITED STATES PATENT OFFICE

103,931

DESIGN FOR A NOVELTY STATUETTE

Morris Greenberg, New York, N. Y.

Application February 19, 1937, Serial No. 67,746

Term of patent 3½ years

To all whom it may concern:

Be it known that I, Morris Greenberg, a citizen of the United States of America, residing in Manhattan, county of New York, State of New York, have invented a new, original, and ornamental design for a Novelty Statuette, of which the following is a specification, reference being had to the accompanying drawing, forming part thereof, wherein,

I claim:

The ornamental design for a novelty statuette, substantially as shown.

MORRIS GREENBERG.
